UNITED STATES PATENT OFFICE

2,500,683

TABLE GAME

George Hammond Hosmer, Arlington, Mass.

Application May 20, 1948, Serial No. 28,086

2 Claims. (Cl. 273—95)

1

This invention relates to table games, and pertains more particularly to a game similar in some respects to lawn or table tennis and adapted to be played on a table or other flat support, either indoors or outdoors.

The principal purpose of the invention is to provide game apparatus which is simple and easy to manufacture and may be packed in a compact box or package, and which affords an interesting and enjoyable contest requiring skill and accuracy in active play without appreciable physical effort.

The several novel features of the improved game will be apparent from the following description of the recommended embodiment of the invention shown in the accompanying drawings, but it will be understood that the structural details of the devices herein illustrated and described may be varied to suit particular tastes or purposes, without departing from the essence of the invention as defined in the appended claims.

In the drawings,

Fig. 1 is a plan view of the playing surface of the game, with a portable net erected across the center of the surface;

Fig. 2 is side view of Fig. 1;

Fig. 3 is an end elevation of Fig. 1, showing the playing surface resting on a flat support;

Fig. 4 is a side view of a striking implement or bat used in playing the game;

Fig. 5 is an end view of the bat, looking to the left of Fig. 4;

Fig. 6 is a top view of a propellable object or missile which is struck by the bat in playing the game;

Fig. 7 is a side view of the missile; and

Fig. 8 is an end view of the missile.

In the particular embodiment chosen for the purpose of illustration, the novel game apparatus comprises a playing surface 11, a net 12 adapted to be supported across the center of the playing surface between posts or standards 13 mounted in base members 14 which may be removably placed at opposite margins of the surface 11, a striking implement or bat 15, and a missile 16 adapted to be struck by the bat and propelled over the net from one end portion of the playing surface to the other end portion thereof. The net divides the playing surface into two identical courts 17.

The playing surface preferably consists of a strip of felt suitably printed, stenciled or otherwise marked to designate the court areas, so that the felt strip may be compactly rolled up for shipment or storage and may be unrolled onto a table or other flat surface, represented by the support

2

28 (Fig. 3), when the game is to be played. It will be obvious, however, that the playing surface may consist of other flexible material, or of rigid material such as fibre board, light wood or metal, or thin plastic, made either in one piece or in hinged or connectable sections.

Each court area 17 is divided into a plurality of blocks or scoring zones 18 which may be substantially square-shaped areas marked on the surface 11, as shown. The zones are arranged in parallel rows longitudinally and transversely of the table, with an equal number on each side of the center or net line; and the respective zones on each side of the net are numbered to designate the scoring value of the individual squares. The values are assessed according to the relative simplicity of returning a tennis ball landing in the corresponding court areas, in the regulation games of lawn or table tennis. For example, the outer corners of the court are given the highest value (shown as "6" in Fig. 1), because a tennis ball landing in those corners is seldom returnable; whereas the center court zones are given the lowest value (shown as "1" in Fig. 1), because tennis shots landing in those areas are relatively easy to return. Hence, the score of a contestant playing my table game will depend upon his skill in placing his shots in the high-scoring zones which correspond to most favorable placement areas in lawn tennis.

The net 12 may be made of string or twine in a conventional manner, or may consist of a fabric or paper strip with the representation of a net printed or otherwise reproduced thereon. The posts 13 and their bases, which may be separable if desired, may be made of wood or plastic, and the net ends may be attached to the posts by any suitable means.

The implements actually used in play consist of the bat 15 and the missile or "rocket" 16, both of which may be made of hard wood, plastic or relatively hard rubber. The use of metal or of soft, resilient rubber is undesirable; but certain types of such materials may be employed.

The bat has a handle portion 19 and a head 20 having opposed striking edges. One striking edge of the head preferably presents a broad, flat striking surface 21, whereas the opposite edge is beveled and pointed at 22 to provide an alternate, relatively narrow striking surface. Thus, either edge of the head may be used in striking the missile, as indicated by the two arrows shown in Fig. 4, according to the position of the missile or the preference of the player.

The missile or rocket is shaped to provide a

relatively long, narrow and flat top surface 23, and an inclined bottom surface 24 at one undercut end, at least, of the piece. Preferably, the bottom surface is beveled or inclined at both undercut ends of the missile, as shown in Fig. 7, so that either end of the top surface may be struck by the bat when the rocket rests upon the curved central portion of its base (Fig. 7), or upon one of the beveled bottom surfaces 24. The proper striking points may be indicated by small circles 25, as indicated in Fig. 6, at both ends of the surface 23. It will be appreciated, however, that a missile or rocket having but one undercut and inclined end may be satisfactorily used in playing the game, as hereafter explained.

The novel game may be played by two or four contestants, as in lawn tennis, each player, or each pair of partners, keeping separate scores as the points are made during play. The player who "serves" or opens the game places the rocket at the baseline or end of the court, preferably at the space marked "Start" in Fig. 1. The rocket is rested in its rounded bottom, or one one of its undercut bottom surfaces, and with one of the undercut ends pointed toward the net. The top surface of said forward pointing end is then struck sharply with the bat, using either the thick and flat edge 21, or the thin and pointed edge 22 of the head 20, as preferred by the player, thereby causing the rocket to jump end over end toward the net.

The object of the game is to so strike the rocket that it jumps over the net and lands on the opposite court of the playing surface, preferably upon one of the high-scoring zones. The length of the rocket is preferably a little greater than the sizes of the squares 18 marked on the playing surface, the views of Figs. 6-8 being enlarged for clarity of illustration as compared with the scale of Fig. 1 which is substantially reduced from actual size. If the rocket finally lands upon two squares of the court, the player scores the value of the higher-scoring square or zone on which a part of the rocket comes to rest.

The opposing player then places the rocket in striking position at the spot where it has come to rest, and returns the shot by striking the forward end with the bat, as aforesaid. If the first shot or play, or any succeeding shot, propels the rocket out of the court or into the net, no score is credited to the player, and the opposing player places the rocket at the "Start" position of his court. If agreed by the contestants, each player may have a second shot from the same position, in the event that the first shot does not land somewhere in the opposite court. The game continues until one player, or one set of partners, has scored twenty-five points, or such other total as may be determined.

It will be apparent from the foregoing that the improved table game is interesting and exciting to play, and may be quickly learned by juvenile as well as more adult participants; that judgment in positioning the missile or rocket and in selecting the striking edge of the bat, as well as skill in execution of the stroke, is necessary for maximum scoring on each shot; and that the game may be played by physically handicapped contestants, without requiring the strength, stamina or physical capabilities necessary for playing the regulation game of table tennis.

I claim:

1. For use in a table game comprising a playing surface adapted to be placed upon a flat support and having scoring zones marked thereon, and a net for centrally dividing said surface into two courts, a missile adapted to be propelled from one court to the other, said missile consisting of a flat-sided and flat-topped rigid object, at least one end of said object having an undercut inclined bottom surface extending from said flat top co-extensive with the flat sides of the object to the bottom thereof, substantially midway of the length of the object, whereby an impact on the flat top adjacent the undercut end of the object resting on its bottom will cause the missile to jump end over end.

2. For use in a table game comprising a playing surface adapted to be placed upon a flat support and having scoring zones marked thereon, and a net for centrally dividing said surface into two courts, a missile adapted to be propelled from one court to the other, said missile consisting of a flat-sided and flat-topped rigid object having at its opposite ends undercut and inclined surfaces co-extensive with the flat sides of the object and extending to the bottom thereof, said bottom having an arcuate surface disposed between said inclined surfaces and substantially in the longitudinal center of the object, whereby the missile rocks on its arcuate bottom and whereby an impact on the top of the missile, at either end portion thereof will cause the missile to jump end over end.

GEORGE HAMMOND HOSMER.
